J. SILVERMAN

LANTERN

Filed March 29, 1924

Joseph Silverman, Inventor

Hardway & Cather
Attorneys

UNITED STATES PATENT OFFICE.

JOSEPH SILVERMAN, OF HOUSTON, TEXAS.

LANTERN.

Application filed March 29, 1924. Serial No. 702,811.

To all whom it may concern:

Be it known that I, JOSEPH SILVERMAN, a citizen of the United States, residing at Houston, in the county of Harris and State of Texas, have invented certain new and useful Improvements in Lanterns, of which the following is a specification.

This invention relates to new and useful improvements in lanterns.

10 One object of the invention is to provide a lantern of the character described having a one piece handle rigidly attached to the base and guard cage, so as to particularly adapt the lantern for use by railroad employees, and the like, requiring a strong and rigid structure.

Another object is to provide a lantern of the character described having a dome which will not ordinarily become so hot as to accidentally burn the user.

A further feature of the invention is to provide a lantern whose parts are so firmly assembled together as to prevent rattling of parts in use.

25 With the above and other objects in view, this invention has particular relation to certain novel features of construction, operation and arrangement of parts, an example of which is given in this specification and 30 illustrated in the accompanying drawings, wherein:—

Figure 1 is a side view of the lantern, partly broken away.

35 Figure 2 is an enlarged fragmentary vertical sectional view of the top part of the lantern; and,

Figure 3 shows a cross sectional view taken on the line 3—3 of Figure 2.

In the drawings, the numeral 1 designates 40 the base of the lantern of conventional type, and which is provided with a perforated, upstanding, annular band 2, whose upper edge is flared and forms a seat 3 for the lower end of the globe 4. The numeral 5 designates a dome whose sides are perforated. The top of the dome is formed of 45 metallic discs 6 and 7, with an asbestos ply 8 between them to prevent the top of the dome from becoming hot enough to burn the user. There is a disc like over-frame 9 having a depending marginal flange 10, which fits around the upper end of the globe. A bolt 11 is fitted downwardly through a central opening in the top whose upper end is formed with an enlarged head 12, and a nut 13 is screwed onto said bolt up against the

underside of the top to clamp said top between said head and nut, and the lower end of said bolt fits loosely through a central bearing in the overframe 9 and has a cotter key 14, to retain said bolt against detachment from the overframe.

There is a cushion member formed of a continuous coil spring having the outer and inner spirals 15 and 16. This cushion member is interposed between the top of the dome and the overframe and holds the latter yielding against the upper end of the globe to prevent rattling.

The dome has a crown flange, or skirt 16 which is hinged at one side in any suitable manner to one side of the top ring 17 of the guard cage 18, and at the other side it is engaged to said ring by the customary spring latch.

The top ring 17, and the upper marginal portion of the band 2 are connected by the radially arranged side members 19, of the cage. Connected to the central portions of the side members 19 there is the annular 50 bracing or reinforcing ring 20.

The handle 21 is formed of a single piece of material of the loop type whose sides are channel like and whose upper portion 22 is tubular, forming a grip.

85 The lower ends of the handle have the inwardly projecting ears 23, 23, which embrace the band 2, on opposite sides, and are riveted thereto and the sides of the handle have the opposing pairs of inwardly extending lugs 24, 24 through which the ring 17 passes. The reinforcing ring 20, also passes through the sides of the handle. A very rigid structure is thus obtained, all of the parts being rigidly secured together, and a lantern thus provided which will withstand rough usage and which is particularly adapted for use as a signal lantern.

90 On opposite sides of the bolt 11 the overframe has crescent shaped sections 25, 25 thrown downwardly to form spreading baffles as well as openings 26, 26, for the passage of smoke and heated air upwardly therethrough, the baffles throwing the heat outwardly and thus deflecting it from the 95 top of the dome prevent the top from becoming excessively hot.

100 What I claim is:—

1. A lantern including a base formed with an upstanding annular band forming a seat, 110 a globe supported by the seat, a guard cage surrounding the globe and rigidly attached

to said band, said cage being composed of an upper and an intermediate ring and radially arranged side members, a hood connected to the upper ring above the globe, a loop type 5 one piece handle whose upper portion is tubular and whose side members are channel like, said rings passing through said side members, flared ears carried by the lower ends of said respective side members, and 10 riveted to the band.

2. A lantern including a base, an upstanding annular rim carried thereby and forming a seat, a globe supported on said seat, a cage rigidly attached to said rim said cage 15 including fixed rings, a one piece handle formed with channel like side members, diverging ears carried by the lower ends of the respective side members and riveted to said rim, oppositely disposed pairs of lugs 20 formed on said side members through which

said rings pass, and a dome attached to the cage above said globe.

3. A lantern including a base, an upstanding annular rim carried thereby, and forming a seat, a globe supported on said seat, 25 a cage rigidly attached to said rim, said cage including fixed rings, a one piece handle formed with channel like side members, the lower end of the respective side members, being fastened to said rim, oppositely disposed pairs of lugs formed on said side members through which said rings pass, and a dome attached to the cage above said globe.

In testimony whereof I have signed my name to this specification in the presence of 30 two subscribing witnesses.

JOSEPH SILVERMAN.
